UNITED STATES PATENT OFFICE

145,240

DESIGN FOR AN ICE CRUSHER OR THE LIKE

James E. Walsh, Burbank, Calif.

Application June 12, 1945, Serial No. 120,036

Term of patent 3½ years

(Cl. D44—29)

To all whom it may concern:

Be it known that I, James E. Walsh, a citizen of the United States of America and a resident of the city of Burbank, in the county of Los Angeles and State of California, have invented a new, original, and ornamental Design for Ice Crusher or the like, of which the following is a specification, reference being had to the accompanying drawing, forming part thereof.

In the drawing:

Figure 1 is a side elevational view of an ice crusher or the like, showing my new design,

Figure 2 is a front elevational view, and Figure 3 is a top plan view.

The opposite side of Figure 1 is the same as shown in Figure 1 except that it has no handle. Portions of the handle in Figs. 2 and 3 and the base in Fig. 2 are shown fragmentarily for convenience of illustrations.

I claim:

The ornamental design for an ice crusher or the like, substantially as shown and described.

JAMES E. WALSH.
